C. L. BURDICK

COIN WRAPPING MACHINE

Filed March 5, 1926

INVENTOR
C. L. Burdick

BY
J. L. Juvne
ATTORNEY

UNITED STATES PATENT OFFICE.

CHARLES LAURENCE BURDICK, OF LONDON, ENGLAND.

COIN-WRAPPING MACHINE.

Application filed March 5, 1926, Serial No. 92,625, and in Great Britain March 10, 1925.

My invention relates to the class of machines by means of which coins or other articles are put up in roll packets in definite quantities as 50 or 100 coins and more particularly applies to the class of machines whereby the ends of the packets are spun or crimped by the well known device of a cup shaped spinning head rotated at a considerable speed. My invention consists of a simple form of holder which may be utilized for making up or closing one end of the coin receptacle and also for holding the packets when filled with coins and closing the remaining open end. I provide means for quickly adjusting the machine or holder for different lengths of packets and for coins of different diameters and means for advancing the holder to meet the spinning head for closing the ends of the packets. In a suitable casing provided with guides I mount an adjustable holder which may be V shaped on its upper surface and arranged for verticle adjustment by having geared racks which engage with toothed wheels one set of which is mounted on a spindle which runs longitudinally within the casing the other set interlocking with these.

The shaft is provided with a handle and spring bolt so that it can be secured in various positions in order to bring the centres of the various coin packets in alignment with the centre of the spinning head.

It is desirable when spinning coin packets to have a rigid stop or support for the ends of the packets to resist the pressure from the spinning head; to obtain this I provide a rod which will move longitudinally within a cylindrical housing. The rod is provided with a handle extended through the housing and arranged to fall in slots cut in the housing in order to fix it for varying lengths of coin packets as required. This rod can either be made a fixture in the casing and in alignment with the centre of the spinning head or can be raised and lowered with the coin holder in which case I provide a projection from the end of the rod positioned eccentrically so that as the rod is turned or rotated 180 degrees it will bring the projection higher or lower to accommodate coin packets of larger or smaller diameter. If the invention is used in connection with a

rigid spinning head, that is one that cannot be advanced longitudinally I provide rollers for the casing which will permit the whole machine to be advanced along suitable guides to bring the coin packets up to the spinning head.

My invention will be understood by the following description with reference to the accompanying diagrammatic drawings of which:—

Figure 1 is a side elevation view,

Figure 1^a is a modified form of the left-hand portion of Figure 1,

Figure 2 a plan view,

Figure 3 is the right hand end elevation view, and

Figure 4 is the left hand end elevation view,

Figures 2, 3 and 4 are drawn to a larger scale than Figures 1 and 1^a.

I provide a platform or base 1 on which the machine is mounted and which may serve also as a support for a motor 2 carrying a spinning head 3. The spinning head may be secured directly to the shaft of the motor as indicated in Figure 1 or it may be secured to a journaled shaft driven from any source of power as indicated by the belt-pulley 5 indicated in Figure 1^a. When the spinner is secured to the motor it is desirable that a bracket 4 with an adjustable centre point (as shown in the drawing) or a ball race be provided to receive the thrust when the spinning operation takes place. A ball-bearing 6 is indicated to take the thrust in the form shown at Figure 1^a. A framework or casing 7 is provided with slots 8—8 in the base which fit over the pins 9—9 secured to the base 1 and which keep the framework in position as it is advanced or withdrawn on its rollers 10—10.

At one end of the casing 7 is a trough shaped member 11 designed to hold the coin packet and which is raised or lowered as required by means of racks 12—12 secured to the inner part of the trough and made to engage with toothed wheels 13—13 and 13'—13'. The set of these wheels 13—13 is secured to a rod or shaft 14 journaled in the casing; this shaft is provided with a handle 15 having a spring bolt 16 which engages with holes 17—17 in the casing to

secure the handle in any desired position. The gear wheels 13—13 enmesh with similar gear wheels 13'—13'.

At the other end of the casing 7 is a rod 18 arranged to slide longitudinally in a tubular casing 19. The rod has a handle 20 which falling in slots 21—21 is so arranged as to provide a rigid end abutment for the coin packets, adjustable for varying lengths 10 of packets.

As slots may be cut on both sides of the tubular casing a great variety of lengths may be accommodated.

The action of the machine is as follows. 15 A sheet of paper having been wrapped around a suitable mandrel with a certain part of paper extending beyond the end of the mandrel it is laid in the trough shaped receptacle and the whole of the machine included in the frame-work 7 is advanced on its rollers so that the extending paper enters the rotating spring cup 3 and is crimped or turned down to the end of the mandrel; when the carton so made is filled with coins 25 or other articles it is again laid in the trough shaped receptacle and the other end spun down to the face of the outermost coin.

When cartons of varying diameter are to be made the height of the trough is regulated by the handle 15 so as to bring the axis of the coin packet in alignment with the axis of the spinning head.

As the lengths of the packets will vary the rod 18 is moved longitudinally in its 35 casing 19 and secured by entering the handle 20 in the appropriate slot to suit the length of the carton or packet.

I claim:

1. In a machine for making and closing 40 coin packets the combination of a holder arranged for the reception of the packets, a rotary head adapted to close down the ends of the packet and guiding means enabling the holder to be advanced relatively 45 to the rotary head to bring an end of the packet into operative engagement with the rotary head.

2. In a machine for making and closing 50 coin packets the combination of a holder arranged for the reception of the packets, a rotary head adapted to close down the ends of the packet means for adjusting the holder relatively to the axis of said rotary head to bring various sizes of packets into alinement 55 with the said axis and means enabling the holder to be advanced relatively to the rotary head to bring an end of the packet into operative engagement with the rotary head.

3. In a machine for making and closing 60 coin packets the combination of a holder arranged for the reception of the packets, a rotary head adapted to close down the ends of the packet, rollers for movably supporting the holder, and guides for the holder

to determine its path of movement relative to the head.

4. In a machine for making and closing coin packets the combination of a holder arranged for the reception of the packets, 70 a rotary head adapted to close down the ends of the packet and an abutment adjustable to hold a packet of any one of various lengths in position upon the holder during the operative engagement of an end of the 75 packet with the said rotary head.

5. In a machine for making and closing coin packets a rotary head, a reciprocatable carrier including a trough-shaped holder for coin packets and a carriage, means to 80 adjust said holder vertically relatively to said carriage, and means to retain said carriage in vertical alinement with said head during reciprocation.

6. In a machine for making and closing 85 coin packets a rotary head, a reciprocatable carrier including a trough-shaped holder for coin packets and a carriage, means to adjust said holder vertically relatively to said carriage, and means to retain said carriage in 90 vertical alinement with said head during reciprocation, together with an abutment adjustable upon said carriage to limit the backward movement upon said holder of any one of a number of different sizes of 95 packet.

7. In a machine for making and closing coin packets a rotary head, a reciprocatable carrier including a trough-shaped holder for coin packets and a carriage, means to adjust 100 said holder vertically relatively to said carriage, and means to retain said carriage in vertical alinement with said head during reciprocation, together with an abutment member having an end facing said rotary 105 head, means to support said member slidably upon said carriage and means to retain said member in an advanced position relatively to said holder to limit the backward movement of a packet on said holder. 110

8. In a machine for making and closing coin packets, a rotary head, a reciprocatable carrier including a holder for supporting a packet, racks upon said holder, pinions engaging said racks, means to rotate said pinions and means to secure said pinions in any one of a number of predetermined angular positions. 115

9. In a machine for making and closing coin packets, a rotary head, a reciprocatable 120 carrier including a holder for supporting a packet and a carriage, racks upon said holder, pinions engaging said racks, means to rotate said pinions and means to secure said pinions in any one of a number of predetermined angular positions, together with an abutment adjustable upon said carriage to limit the backward movement upon said holder of any one of a number of different sizes of packet. 125

10. In a machine for making and closing coin packets the combination of a rotary head, a packet carrier, means to adjust said carrier as to alinement with said head for use with any one of several diameters of packet, means to adjust said carrier to accommodate packets of different lengths, and means to support and guide said carrier in its movement relative to the head. 10

In testimony whereof I affix my signature.

CHARLES LAURENCE BURDICK.
